UNITED STATES PATENT OFFICE.

FREDERICK H. BUSBY, OF SAN FRANCISCO, CALIFORNIA.

STOVEPIPE-FASTENER.

SPECIFICATION forming part of Letters Patent No. 723,984, dated March 31, 1903.

Application filed December 12, 1902, Serial No. 134,890. (No model.)

To all whom it may concern:

Be it known that I, FREDERICK H. BUSBY, a citizen of the United States, residing in the city and county of San Francisco, State of California, have invented certain new and useful Improvements in Stovepipe-Fasteners; and I do hereby declare the following to be a full, clear, and exact description of the same.

My invention relates to the class of fasteners adapted for securing stovepipes in the chimney-hole.

The objects of my invention are simplicity in construction, ease in adjustment, and efficiency in operation. These are secured by the provision of a readily and economically made device capable of being applied with facility and adapted not only to support the stovepipe, but also to limit the insertion of said pipe into the chimney-flue, so that it will not abut against the inner flue-wall, and thereby interrupt the draft and passage of the smoke, and adapted also to lock itself in the flue so that it will neither move in nor out, thereby completely fastening the stovepipe.

My invention consists in the novel constructions and combinations of parts constituting the stovepipe-fastener and which I shall now fully describe and claim by reference to the accompanying drawings, in which—

Figure 1 is a perspective view of the fastener, showing the locking-strap in the plane of the stop-strap, both parts being in position to be compressed laterally to enter the stovepipe-hole. Fig. 2 is a perspective view of the fastener, showing the locking-strap turned at right angles to the stop-strap to its locking position. Fig. 3 is a vertical section of a chimney, showing the application of the fastener to the stovepipe and the chimney. Fig. 4 is a cross-section of same.

A is a strap formed of metal sufficiently thin to be compressible or elastic. This strap has a bow end *a* and extended arms *a'* and may be termed the "stop-strap."

B is a strap of similar elastic or compressible material. It is annular or ring-shaped in contour, having a little less radius than the radius of the bow *a* of strap A. This strap may be termed the "locking-strap." Strap B is pivoted at *b* within strap A and is adapted to be turned on its pivots to lie in the

plane of strap A, as shown in Fig. 1, or to lie in a plane at right angles thereto, as shown in Fig. 2.

C, Figs. 3 and 4, is a chimney of any kind, having a flue *c* and a stovepipe-hole *c'*. In the normally expanded condition of the straps A and B they will not pass into the stovepipe-hole *c'*, and to secure this result they are purposely made wider than the diameter of the hole; but if when the annular locking-strap B is lying within and in the plane of stop-strap A, as in Fig. 1, they be compressed from each side they will elongate sufficiently to allow them to pass into the stovepipe-hole. When they have entered sufficiently transversely of the chimney-flue *c* to let the forward arc of the locking-strap B clear the front wall of the flue, said locking-strap is then by the inserted hand turned on its pivots *b* to a plane at right angles to strap A, as in Fig. 2, in which position it lies in the plane of the length of the flue, Fig. 3, and directly behind or within the front wall of said flue. Having been relieved of its entering compression, the locking-strap B expands to its full diameter, and its shape is then such that it is too large to be withdrawn from the stovepipe-hole, Fig. 3, and the device is thereby securely held in the chimney, with the bow end *a* of stop-strap A near or in contact with the back wall of the flue, Figs. 3 and 4, the arms *a'* projecting forwardly out of the stovepipe-hole and the locking-strap B disposed up and down behind the inner rim of said hole and too large to come out.

The stovepipe D is fitted through hole *c* and its end is limited in its inward projection by contact with the bow end *a* of stop-strap A far enough from the back wall of the flue to permit free draft and passage of the smoke. Outside the hole the stovepipe may be secured to the arms *a'* of strap A in any suitable manner. I have here shown a couple of nails *d* for this purpose, Fig. 4.

If desired, though it is not essential, small angle-brackets *a'* may be secured to the outer surfaces of the arms *a'*, which said brackets may be secured to the face of the chimney; but it is obvious that without these brackets the device is securely held in place, for it cannot be pushed in farther than the contact of the bow end *a* with the inner or back wall of the flue, nor can it be pulled out farther than

the contact of the locking-strap B with the inner surface of the front wall of the flue. To remove the device, the stovepipe is first released from arms *a'* and withdrawn. Then 5 the hand is inserted in hole *c* and the locking-strap B is turned down to the plane of stop-strap A, as in Fig. 1. Then by pulling on the arms of stop-strap A both straps will be compressed laterally and will pull through 10 and out of the hole.

To provide for economy in packing numbers of these devices for transportation, I deem it best to sever the locking-strap B at 15 about the middle of its front arc, as seen in Fig. 1, making the severed ends overlap, whereby they may, when the device is about to be used, be riveted by a rivet *b'*. When being packed, both straps may be straightened out, lying on one another, and thus presenting 20 straight strips adapted to be secured in bundles with advantage as to space. When a fastener is used, the stop-strap A is bent to its bowed form and the locking-strap B is curved to its annular form and its severed 25 overlapping ends united by rivet *b'*.

Having thus described my invention, what I claim as new, and desire to secure by Letters Patent, is—

1. A stovepipe-fastener comprising a laterally-compressible member to which the stovepipe is to be secured, and a second compressible member pivoted to the first member and adapted to be turned to the plane of said member and to a plane at an angle thereto, 30 both members being normally too wide to enter the stovepipe-hole, but laterally compressible therethrough when they lie in the same plane, whereby when entered into the chimney-flue the second member when turned 35 to an angle with the first member engages behind the front wall of the flue.

2. A stovepipe-fastener comprising a laterally-compressible member to the outer end of which the stovepipe is to be secured, the inner end of said member forming a stop, and a second compressible member pivoted to the 45 first member and adapted to be turned to the plane of said member and to a plane at an

angle thereto, both members being normally too wide to enter the stovepipe-hole, but laterally compressible therethrough when they lie in the same plane, whereby when entered into the chimney-flue the inner stop end of the first member limits its insertion, and the second member when turned to an angle with the first member engages behind the front wall of the flue. 50

3. A stovepipe-fastener comprising a laterally-compressible stop member formed with a bowed end and extending arms, the latter to receive and secure the stovepipe, and an annular compressible locking member pivoted within the stop member and adapted to be turned to the plane of said stop member and to a plane at an angle thereto, both members 60 being normally too wide to enter the stovepipe-hole, but laterally compressible therethrough when they lie in the same plane, whereby when entered into the chimney-flue, the bow end of the stop member forms a stop 65 for the fastener and for the stovepipe, and the annular locking member when turned to a plane at an angle to the stop member engages behind the front wall of the flue and locks the fastener against withdrawal. 70

4. A stovepipe-fastener comprising the laterally-compressible bowed strap with its arms for receiving and securing the stovepipe, and the annular compressible strap pivoted at its sides in the bowed strap, and adapted to be turned to and from the plane of the bowed strap. 80

5. A stovepipe-fastener comprising the laterally-compressible bowed strap with its arms for receiving and securing the stovepipe, and the annular compressible strap pivoted at its sides in the bowed strap and adapted to be turned to and from the plane of the bowed strap, said annular strap being jointed in its forward arc. 85

In witness whereof I have hereunto set my hand.

FREDERICK H. BUSBY.
